(57) **CLAIM**

The ornamental design for the bottom of containerized air
 compressor, as shown and described.

DESCRIPTION

FIG. 1 is a top plan view of a bottom of containerized air
 compressor of our new design;

FIG. 2 is a bottom plan view thereof;

FIG. 3 is a side elevational view thereof;

FIG. 4 is a side elevational view of the side opposite FIG. 3;

FIG. 5 is a left end view thereof;

FIG. 6 is a right end view thereof;

FIG. 7 is a top perspective view thereof; and,

FIG. 8 is a bottom perspective view thereof.

Dashed lines appearing in FIGS. 1-8 of the drawing repre-
 sent environment and form no part of the claimed design.

1 Claim, 8 Drawing Sheets
